LIGHTING FIXTURE TROFFER AND
LATCH THEREFOR

Julio A. Pascucci, Meriden, Conn., assignor to The Miller Company, Meriden, Conn., a corporation of Connecticut

Filed Feb. 13, 1958, Ser. No. 714,979
4 Claims. (Cl. 240—51.11)

This invention relates to lighting fixtures and more specifically to a novel and improved troffer particularly adaptable for use with fluorescent lamps and arranged and constructed to facilitate installation in ceiling and other openings without the need for auxiliary mounting means such as yokes and the like.

Prior fluorescent fixtures for flush type mounting have generally been made with one-piece troffers which have necessitated the use of special mounting means such as fixture spanning yokes or other similar devices. In the case of yokes, they were generally secured to ceiling members and had to be accurately positioned in the opening for engagement with cooperating means on the fixture when inserted in the ceiling opening. With this invention, special mounting means are not needed and the fixture is designed and arranged to greatly facilitate installation in a ceiling opening.

Another object of the invention resides in the provision of a novel and improved troffer for electric lighting fixtures that is characterized by its simplicity, relatively low cost and ease of installation.

Still another object of the invention resides in the provision of a novel and improved troffer for lighting fixtures formed of a number of independent elements that may be assembled within the ceiling opening and secured therein without the need for auxiliary supporting members.

A still further object of the invention is a novel and improved troffer for fluorescent and other lighting fixtures formed of a plurality of individual elements that may be quickly and easily assembled without the need for special tools and equipment.

A still further object of the invention resides in the provision of a novel and improved troffer for lighting fixtures.

The above objects and advantages will become more apparent from the following description and accompanying drawings forming part of this application.

In the drawings:

FIG. 1 is a perspective view of a lighting fixture in accordance with the invention;

FIG. 2 is an exploded perspective view of certain elements of the fixture shown in FIG. 1;

FIG. 3 is a plan view of the fixture shown in FIGS. 1 and 2;

FIGS. 4 and 5 are cross sectional views of FIG. 3 taken along the lines 4—4 and 5—5 thereof;

FIG. 6 is a fragmentary section of the fixture as shown in FIG. 4 illustrating certain steps in the assembly thereof;

FIG. 7 is a cross sectional view of FIG. 3 taken along the line 7—7 thereof;

FIGS. 8 and 9 are cross sectional views of FIG. 7 taken along the lines 8—8 and 9—9 thereof;

FIG. 10 is an exploded perspective view of the locking means for securing the lens structure or closure in place as shown in FIG. 1; and

FIG. 11 is an exploded perspective view of a hinge for attaching the lens structure to the fixture and cooperating with the locking means of FIG. 10 to support the lens structure.

The fixture in accordance with the instant invention is shown in FIGS. 1 and 2 and comprises a top member

2

10, a pair of side members 11 and 12, a pair of end members 13 and 14 and a transparent or translucent closure 15. As will be shown, each of these elements is fabricated individually and are arranged and coordinated to facilitate assembly and installation of the fixture within a ceiling opening. For purposes of simplicity, the lighting sources such as fluorescent or other lamps have been omitted, as they do not form part of the invention.

In the illustrated embodiment of the invention the top section 10 includes a raised center portion 16 to provide an elongated channel and forming part of a wire way for connecting a fluorescent type lighting source. The sides of the member 10 are bent upwardly as indicated at 17 and then outwardly as indicated at 18 with the flanged portion 18 being substantially in the plane of the center portion 16. The ends of the center section 16 are provided with slotted openings 19 and the ends of the flanges 18 are provided with similar slotted openings 20. These openings 19 and 20 cooperate with tabs 21 on the end sections 13 and 14 in the assembly of the fixture. The upwardly formed portions 17 of the top section 10 also include slots 22 for cooperation with tabs 23 and the side sections 11 and 12 for securing the side and top sections together.

25 The side sections 11 and 12 are identical in configuration and each includes a sloping panel part 24 having a substantially horizontally formed top portion 25 which carries the downwardly formed ears or tabs 23. The bottom edge of each panel 24 is bent downwardly as indicated at 26, then outwardly to form a portion 27 substantially at right angles with the member 26. The edges then terminate in a U-shaped structure having substantially vertical leg portions 28 and 29 and a bottom portion 30. In addition to the tabs 23, the side sections 30 further include a pair of slots 31 at each end of the panel 24 for cooperation with tabs 32 of the end sections 13 and 14. The outwardly extending portion 27 is provided with two sets of openings with each set including individual openings 33, 34 and 35 which may be observed more clearly in FIG. 10. The leg 28 of the U-shaped edges each include a pair of openings 36 for cooperation with hinge members on a closure panel 15.

35 The end sections 13 and 14 are identical and each has a configuration that will coordinate with the top 10 and sides 11 and 12 to form the completed closure. The bottom edge of each end panel is bent inwardly as indicated at 37 and then downwardly to form a section 38 substantially parallel to the plane of the side member. The bottom edge of the panel portion 38 is formed inwardly as indicated at 39 and includes offset tabs 40 on the ends and a pair of openings 41 for attachment of the U-shaped clips 42, shown more clearly in FIG. 5.

45 In addition to the basic housing members described above the ends of the fixture in accordance with the invention further include a pair of elongated members generally denoted by the numeral 43 which are adapted to be secured to the end members with the latter in place in the ceiling opening. Each member 43 includes an upper elongated L-shaped member having leg portions 44 and 45 and lower L-shaped members having leg portions 46 and 47. The member 46 is secured to the bottom face of the leg 45 with the leg portion 47 extending outwardly and terminating in a plane substantially in line with the leg portion 44 of the upper L-shaped member. The leg portion 44 further includes a pair of rectangular openings 48 for cooperation with the clips 42.

To assemble the elements of the invention described thus far, the side panels 11 and 12 are placed in engagement with the top panel 10 by insertion of the tabs 23 in the cooperating openings 22, as may be seen in FIG. 6. With the side panels in place and moved inwardly a sufficient distance to clear the tabs 32 on the

end panels 13 and 14, the end panels are then engaged with the top panel by inserting the offset tabs 21 in openings 19 and 20 as previously described. The offset tabs 21 have offset portions 22 displaced downwardly from the plane of the tab base so that when the side sections 13 and 14 are in a vertical position as shown in FIG. 5, they are firmly locked to the top section 10. The fixture is now in a partially assembled position and, if desired, the side members 11 and 12 may be moved outwardly to the position shown in FIG. 6 wherein the openings 31 are in partial engagement with the inwardly extending tabs 32 of the end section.

The fixture in accordance with the invention is preferably mounted in a ceiling opening having an exposed T-member 49, as shown in FIG. 6, surrounding the edge of the opening. The fixture is placed in the opening and if desired, the end sections may be wired to a portion of the T-member 49 by means of the opening 40' in the end tabs 40. This procedure merely facilitates installation and does not provide basic support for the fixture. After the fixture has been inserted, the side members 11 and 12 are moved outwardly to the position shown in FIG. 4 so that the bottom portion 33 of the U-shaped edge portions of the side members rest on the exposed portions of the T-shaped member 49. In this position the openings 31 of the side sections are in full engagement with the tabs 32 whereupon a portion 32' of each tab 32 is bent to prevent disengagement of the side and end sections. After securing the side sections in place the end members 43 are then installed by engaging the clips 42 with the openings 48 and then rotating the clips 42 through an angle of about 90 degrees to the position shown in FIG. 4. With the side members 43 in position the lower edge portion 47 rests on the exposed portion of the T-shaped member 49, as shown more clearly in FIG. 5, and the bottom flanges 39 of the side members engage the under surface of the leg members 45. The fixture housing is now complete except for the installation of the closure member 15 which is adapted to be received within the recessed opening bounded by the side walls 28 and the end walls 46.

The closure member, while it may have any desired configuration, preferably includes a metal frame 50 of generally U-shaped configuration as shown more clearly in FIG. 11. The bottom part of this structure has an upwardly formed flange part 51 upon which the translucent or other light transmitting closure member 52 is carried. The upper edge of the member 50 has an upwardly formed flange 53 as shown. The light transmitting member 52 may be held securely in the frame 50 by any suitable means such as appropriate springs 54 as will be observed in FIG. 7. One side edge of the closure 15 is provided with hinge portions 55 as shown in FIG. 11 and spaced to cooperate with the openings 36 in the side members. Each hinge 55 has a portion 56 extending outwardly from the frame member 50 and a second portion of L-shaped configuration extending downwardly. The member 57 includes an outwardly extending elongated tab portion 58, forming the L configuration, which cooperates with the openings 36. To insert the hinge portions 55 in the openings 36, the closure member 15 is held in a substantially vertical position and the tab is inserted through the elongated portion of the opening 36. After engagement the closure member can be lowered and the narrow section of the hinge portion 57 engages the narrower portion of the opening 36. Since the outwardly extending tab 58 now engages the wall 28 of the side member, the closure 15 is locked in place and will be self supporting.

The other side of the closure member 15 includes a pair of latches generally denoted by the numeral 59 as shown in FIG. 10. It has a flat base portion 60 with a downwardly curved part 61 and an upwardly extending portion 62 secured to one edge of the base 60. The portion 62 has a curved hook-like member 63 and an out-

wardly extending member 64 having an upper, tapered edge 65. Prior to assembly of the fixture within the ceiling opening as previously described, one side section of the fixture is provided with a pair of spring-like members 66. One end of this member 66 includes a pair of downwardly extending tabs 67 which engage the opening 33 having a keyhole configuration so that the tab 67 can be inserted therein and then moved longitudinally to lock the spring in the narrowed section of the opening 33. The central portion of the spring 66 has an opening 34' which registers with the opening 34 in the wall portion 26. That part of the spring to the left of the opening 34' as shown in FIG. 10 is formed upwardly as indicated at 68 to form a V-shaped configuration and the outer end of this V-shaped configuration is provided with a tab 69 adapted to register and engage the opening 35 when the spring 66 is locked in position. The latch 62 is provided with an opening 62' for pivotal attachment to the edge of the frame member 50 as shown in FIG. 7, so that the base 60 underlies the adjoining frame part. With the latches 59 in the open position as shown to the right of FIG. 5, the closure member 15 can be moved to the closed position as indicated in FIG. 1 wherein the latches are then moved in a counter-clockwise direction to the position shown to the left of FIG. 5 with the upper curved portion 63 in engagement with the V-shaped portion 68 of the spring 66.

With the invention as described above it is apparent that the flush-type fixture can be mounted within a ceiling opening having a suitable fixture supporting ledge extending inwardly from the periphery of the opening. By reason of the novel and improved arrangement of elements, the entire fixture can be installed without the need for special tools or the insertion of screws or other similar fastenings. Similarly, the fixture may be quickly and easily removed for repair and replacement. Another important advantage resides in the ease of fabrication of the elements and the utilization of identical end sections and side sections. Since the fixture may be easily and quickly assembled, it can be shipped in knock-down form, which results in materially reduced shipping costs.

While only one embodiment of the invention has been illustrated and described, it is apparent that modifications, alterations and changes can be made without departing from the true scope and spirit therefrom as defined by the appended claims.

What is claimed is:

1. A lighting fixture troffer comprising a relatively flat top section of rectangular configuration having two sets of parallel edges, a pair of end sections, means detachably securing one edge of each of said end sections to one edge of one of said sets of edges of said top section and depending therefrom, a rectangular ceiling opening having inwardly extending flange-like members on at least two opposing edges, a pair of side sections each detachably and hingeably connected to one edge of the other set of parallel edges, said side sections being movable inwardly one toward the other and between the end sections, said side sections upon insertion of the fixture in said ceiling opening being moved to outward positions with the lower edges of said side sections engaging said flange-like members, means for securing said side sections in said outward positions to said end sections to form a rigid structure and elongated members including means securing them to said end sections with the lower edge of each of said members lying substantially in a plane defined by the lower edges of said side sections when in said outward position to completely close said opening.

2. A lighting fixture troffer according to claim 1 wherein the lower edges of the side and end sections form a rectangular frame and said troffer further includes a light transmitting closure carried within said frame, said closure being removably hinged at one edge to the lower edge of one of said side sections and carrying locking means on the opposing edge removably engaging coop-

erating means on the lower edge of the other of said side sections to secure the closure in its closed position.

3. A lighting fixture troffer according to claim 2 where-
in the lower edge of one of said side sections includes a pair of L-shaped openings and said closure member in-
cludes a pair of outwardly extending bracket members each having an angularly disposed end portion of a con-
figuration similar to said openings, said brackets and openings forming a hinged support for said closure.

4. A lighting fixture troffer according to claim 1 where-
in the said locking means comprises an arcuate member pivotally secured to said closure member and the last said means includes an opening and spring member adjoining said opening whereby said arcuate member is movable operatively through said opening and into engagement with said spring, said spring holding the arcuate member

in engagement therewith to secure the closure member in the closed position.
